R. A. BREUL

TRANSFORMABLE WALKING STICK

Filed June 1, 1922

Richard A. Breul, INVENTOR.

UNITED STATES PATENT OFFICE.

RICHARD A. BREUL, OF BRIDGEPORT, CONNECTICUT.

TRANSFORMABLE WALKING STICK.

Application filed June 1, 1922. Serial No. 565,220.

To all whom it may concern:

Be it known that I, RICHARD A. BREUL, a citizen of the United States, residing at Bridgeport, in the county of Fairfield and 5 State of Connecticut, have invented a new and useful Transformable Walking Stick, of which the following is a specification.

The object of this invention consists in the construction of a composite walking stick, 10 instantly separable into parts adapted to likewise form a serviceable triangular stool, some parts thereof also being made useful for other purposes, as hereinafter described. A device comprising an analogous forma- 15 tion and carrying out the same object by a different construction, is the subject of a previous application for patent by me, and several features of improvement are similar in both inventions.

20 In the accompanying drawings Fig. 1 represents the walking stick form of my device, and Fig. 2 the stool formation thereof. Fig. 3 is the enlarged upper portion, and Fig. 4 the lower part of rod *h* of the device, 25 while Fig. 5 is a still more enlarged upper end view of the lower part of the walking stick, formed by rods *h* and *g*. Figs. 6 and 7 are likewise enlarged views of opposite ends of rod *a*, and Figs. 8 and 9, also enlarged front views of both end portions of such rod *a*, containing the upper ends of the stool formation legs *g* and *h*. In Fig. 10 is seen the head of the walking stick containing the handle, in Fig. 11 a rod body 35 connecting ferule, and Fig. 12 is a bottom view of the Fig. 9 illustration of rod *a* and parts thereon, these views being also on an enlarged scale.

The walking stick illustration Fig. 1 has 40 a preferably wooden body of same size throughout, consisting of an upper rod "*a*" of preferably square form and of two rectangular rods *g* and *h* of like size, both together being of same shape and size as rod "*a*", all the edges of the three rods being somewhat chamfered and rounded, (see Figs. 5 and 6). Both end portions of rod "*a*" and also the upper portions of rods *g* and *h*, as combined together (see end view 45 shown in Fig. 5), are reduced to a cylindrical shape of same diameter as the square body of "*a*", the rounded upper portion of "*a*" being supplied with a headed ferule or shell *c*, while the lower portion thereof and the described 50 cylindrical formation of the combined rods 55

g and *h* are united by the sheet metal ferule *b*, as apparent in Fig. 1. While this ferule is permanently attached to rod "*a*", as will be described hereafter, the cylindrical portion formed on the upper ends of combined 60 rods *g* and *h*, which together comprise the lower portion of the walking stick, is of proper size to frictionally engage the extended free portion of ferule *b* in the same manner as separable fishing rods are united 65 and adjusted. Rods *g* and *h* are loosely pivoted together near their lower ends, (see Figs. 2 and 4) by a pivot, *o*, passing through washers *k*, over the outside of each rod. Rubber tips (see *i*, Fig. 4), of about same 70 form and size as the body part of rods *g* and *h* are attached to the lower reduced ends of these rods. A handle, preferably consisting of a shell, *d*, secured in an aperture *d'* of ferule *c*, and of a shell *e*, frictionally 75 engaging and slidably held on shell *d*, (see Figs. 1, 9, and 10), is attached to the upper end of rod "*a*", the general construction of such a walking stick being thus completely 80 shown.

In order to make the above described parts of a walking stick available for the formation of a stool as illustrated in Fig. 2, some of these parts have to be specially constructed and arranged as shown hereafter. 85 Rod "*a*", as shown in Fig. 2, forms the seat portion of my stool device, both end portions of "*a*" contain slots crosswise and centrally located therein for the reception of the upper, semi-circular portions of rods *g* and *h* (see *a'* and *a''*, Figs. 8 and 9, and also Figs. 6 and 7 for width of said slots). As further shown in Figs. 11 and 12, the 90 ferules *b* and *c*, which otherwise would entirely surround and close up said slots, have on their bottom sides only, apertures of the shape of said end portions of rods *g* and *h*, such apertures disposed to be exactly in alignment with said slots *a'* and *a''* respectively. In Fig. 6 the right end of rod "*a*" 100 is shown, with the ferule *c* and handle parts *d* removed therefrom.

It is apparent herefrom, that rods *g* and *h*, when arranged in V shape may be readily attached to rod "*a*", to form a stool of triangular shape, by entering the upper semi-circular portion *g'* of rod *g*, through aperture *b'* in ferule *b*, into and upwardly along in slot *a'*, and at the same time introducing the similar end portion *h'* of rod *h* through 110

slot c' of ferule c into slot a'' of rod "a". There being no corresponding aperture on the upper side of said ferules, the upper ends of rods g and h will abut and rest 5 against the inner wall of the ferrules, and additional rest and hold for this connection of the rods is provided by the wires f and f' , as to be described. These wires or pins (see f and f' , Figs. 8, 9, and 12), secure the 10 ferules b and c to rod "a", pass entirely through them, and also centrally through the entered portions of rods g and h , such end portions being provided with slots (see 15 h'' , Fig. 3), allowing the withdrawal and insertion of these rods.

Two other pins, f'' and f''' also pass through ferules b and c , respectively, and rod "a", in like manner as those just described, except in a location and for the purpose 20 of providing a rest for the outer edges of the entered portions of rods g and h , the inner edges thereof resting against and guided by the inner walls of slots a' and a'' (see a''' , Fig. 12).

By such construction rods g and h forming the leg portions of this stool are detachably and firmly held in rod "a", the seat portion of the device, secure against a pressure from above, and against any sidewise 30 exerted tendency or force.

It is apparent from the foregoing that the device thus described readily serves for both purposes, that of a walking stick, and also of a stool to sit on, the feet of the occupant 35 affording sufficient balance, and additional restfulness may be obtained by placing the stool near a wall or similar object, to serve as a support for the back of a person. It is equally apparent that the change from one 40 formation to the other is almost instantly accomplished, and that both are of sufficient

stability for all the use any of these formations may be subjected to.

Furthermore the hollow handle may serve as a match box or receptacle for medicine or other small matter, and inch and yard measurement graduation may be applied to the inner faces of rods g and h , as indicated on g , Fig. 2. Also, when simply taken apart, and the three rods laid parallel upon each other, the device occupies but little space, and may readily be carried in a valise or economically boxed and mailed.

I claim:

1. A device consisting of a rod, ferules attached to both ends thereof, and extending therefrom, and of two rods journaled together by a pivot, said two rods adapted to rest upon each other, and to engage together a ferule on the first stated rod, and also adapted to be spread apart, the free end portions arranged to enter slots in both end portions of the first stated rod, and coinciding apertures in the lower sides of the ferules enclosing the slotted end portions of said rod.

2. In a triangular stool, constructed of a rod forming the seat portion, and of two rods forming the leg portion, ferules on and extending beyond the ends of the seat portion, coinciding apertures through one side of said ferules and through said rod, wire rods attaching the ferules to the rod and passing centrally through said apertures, the upper portions of each end of the two rod formation adapted to engage one of said coinciding apertures, slots in the upper end portions of said two rods, each adapted to be guided by and to rest against one such wire rod.

RICHARD A. BREUL.
